SECONDARY RECOVERY METHOD FOR PETROLEUM BY FLUID DISPLACEMENT

Sidney M. Fouiks, Irving, Tex., assignor to Socony Mobil Oil Company, Inc., a corporation of New York
Filed Aug. 20, 1959, Ser. No. 835,073
5 Claims. (Cl. 166—9)

This invention relates to the secondary recovery of petroleum from a subterranean formation and relates more particularly to the secondary recovery of petroleum from a subterranean formation by methods involving displacement of petroleum within the formation by means of an injected fluid.

Petroleum is usually recovered initially from most subterranean formations as a result of gas pressure or natural water drive forcing the oil from the petroleum-bearing formation, or reservoir, to a producing well and to the surface of the earth. As recovery of petroleum from the formation continues, the reservoir energy gradually decreases and finally becomes insufficient to force the petroleum to the surface of the earth, although a major portion of the petroleum still remains in the reservoir. To recover further petroleum from these reservoirs after the reservoir energy has begun to decline, secondary recovery methods may be employed. Various of these secondary recovery methods involve displacement of petroleum within the formation to a production, or output, well by injection of a displacing fluid, either a gas or a liquid, into the formation through an injection, or input, well.

In secondary recovery methods employing a displacing fluid, the displacing fluid travels from an injection well to a production well in pathways, other things being equal, determined by the number and relative position of the injection and production wells. The petroleum within the pathways of travel of the displacing fluid in the formation will be the petroleum susceptible of recovery by the procedure employed. The remainder of the petroleum, lying outside the pathways of travel of the displacing fluid, will not be recoverable by that particular procedure. The shape of the area of the formation within the pathways of travel of the displacing fluid is termed the "sweep pattern" and the ratio of the area within the sweep pattern to the total area is termed the "sweep efficiency." Practical operations, from the standpoint of economy, require a maximum sweep efficiency commensurate with the number of injection and production wells. Conventionally, the injection and production wells are arranged in regular, uniform patterns with an injection well surrounded by a plurality of production wells. While high areal sweep efficiencies are obtained with these well patterns, still higher efficiencies are desirable.

It is an object of this invention to improve the extent of recovery of petroleum from a subterranean formation. It is another object of this invention to obtain a greater sweep efficiency in a secondary recovery operation employing a displacing fluid. Further objects of the invention will become apparent from the following detailed description.

In accordance with the invention, in a secondary recovery operation for petroleum oil wherein a displacing fluid is injected into a subterranean formation through a central well and petroleum oil is displaced in the direction of and produced from a plurality of wells surrounding the central well, there are provided two steps. In the first step, the displacing fluid is injected into the central well and petroleum oil is produced from at least every one of the surrounding wells until breakthrough occurs at these surrounding wells. In the second step, with the central well shut off, the displacing fluid is injected into every other one of the surrounding wells and the petro-

leum oil is produced at the remainder of these surrounding wells.

FIGURES 1 and 2 are schematic diagrams illustrating an embodiment of the invention.

FIGURES 3 and 4 are schematic diagrams illustrating the sweep patterns obtained with the embodiment of the invention illustrated in FIGURES 1 and 2.

FIGURES 5, 6, and 7 are schematic diagrams illustrating other embodiments of the invention.

FIGURES 8 and 9 are schematic diagrams illustrating the sweep patterns obtained with the embodiment of the invention illustrated in FIGURES 5 and 6.

FIGURES 10 and 11 are schematic diagrams illustrating the sweep patterns obtained with the embodiment of the invention illustrated in FIGURE 7 and FIGURE 6.

Referring now to FIGURE 1, field 20 overlying a petroleum reservoir is provided with a plurality of wells. These wells are arranged in a regular, geometric, uniform pattern. Further, each well is located at the corners of a square. The pattern of the wells may also be described as being such that any one well, a central well, is surrounded by eight wells equidistantly spaced from each other.

For purposes of simplicity and description, reference

25 will be made in FIGURE 1, as well as FIGURES 2, 5, 6, and 7, to the wells within a circumscribed area. In FIGURE 1, this area is indicated by the numeral 21. However, it will be understood that operations with respect to

30 the other wells in the fields will be similar to those described with respect to the wells in the circumscribed area. In the figures, a ring containing a central dot signifies an injection well, a solid circle represents a production well, and a cross represents a well which has been shut in.

35 In the circumscribed area 21 of FIGURE 1, well 22 is located at the center of the area. Located at the midpoint of each of the lines describing the circumscribed area are wells 23, 24, 25, and 30, respectively. Located at the four corners formed by the intersections of the four lines describing the circumscribed area are wells 31, 40 32, 33, and 34, respectively.

45 In the first step of the process, displacing fluid is injected into central well 22. In this first step, petroleum oil is produced from wells 23, 24, 25, and 30. Thus, these wells are operated as production wells. Additionally, in the first step, wells 31, 32, 33, and 34 are shut in.

The displacing fluid injected into well 22 passes through the petroleum reservoir underlying the field into the direction of the wells 23, 24, 25, and 30. The pathways 50 of the displacing fluid migrating from the well 22 to any one of the wells 23, 24, 25, and 30 are affected by the presence of each of the wells to each other. Many of these pathways are curvilinear and, thus, portions of the reservoir other than those in a direct line between well 22 and any one of wells 23, 24, 25, and 30 are swept by the displacing fluid. With continued injection of the displacing fluid into well 22, breakthrough of the displacing fluid into each of wells 23, 24, 25, and 30 eventually occurs.

60 With breakthrough of the displacing fluid into each of the four production wells, the shape of the area swept by the displacing fluid, i.e., the sweep pattern, will be as indicated in FIGURE 3. This sweep pattern is the dark area 35 within the circumscribed area 21. The ratio of the area 35 to the area 21 varies with the ratio of the mobility of the displacing fluid to the mobility of the displaced fluid. Mobility is defined as the ratio of the permeability of the reservoir to the fluid and the viscosity of the fluid. With a mobility ratio of 1:1, the area 35 will constitute 45.5 percent of the area 21. Thus, with the well pattern illustrated in FIGURE 1, the area swept

by the first step of the process, with a mobility ratio of 1:1, will be 45.5 percent of the total area of the reservoir lying between the wells.

In the second step of the process, referring to FIGURE 2, central well 22 is shut in. Wells 23, 24, 25, and 30 are operated as injection wells, and wells 31, 32, 33, and 34 are operated as production wells. The injection wells will now be located at the midpoints of the lines describing the circumscribed area 21 and the production wells will be located at the intersections of the lines describing the circumscribed area 21.

The displacing fluid passes through the formation from each of the injection wells into the direction of the production wells. Petroleum is produced from each of the production wells and eventually breakthrough of the displacing fluid occurs at each of the production wells. The pathways of the displacing fluid migrating through the formation are affected by the injection and production wells and many of the pathways are accordingly curvilinear. The sweep pattern at breakthrough following the second step of the process is as indicated in FIGURE 4.

Referring to FIGURE 4, the sweep pattern is the dark area 40. The major portion of the circumscribed area 21 is included within the area 40. The only portion of the circumscribed area not included is the two small areas located near each of the output wells 31, 32, 33, and 34. The ratio of the area 40 to the area 21 will depend upon the mobility ratio. With a mobility ratio of 1:1, the area 40 will constitute 91 percent of the area 21. Thus, with the well pattern illustrated in FIGURES 1 and 2, the total area swept by the procedure of the invention for a mobility ratio of 1:1 will be 91 percent of the total area of the reservoir lying between the wells.

Another well pattern is illustrated in FIGURE 5. Field 41 overlies a petroleum reservoir and, similar to field 20, is provided with a plurality of wells. These wells in field 41 are also arranged in a regular, geometric, uniform pattern. Further, each well is located at the corners of a hexagon. The pattern of the wells may also be described as being such that any one well, a central well, is surrounded by six wells equidistantly spaced from each other.

Well 42 lies in the center of circumscribed area 43. Located at the intersections of the six lines describing the circumscribed area are wells 44, 45, 50, 51, 52, and 53, respectively. In the first step of the process, displacing fluid is injected into central well 42. Petroleum is produced from wells 45, 51, and 53 and, thus, these wells are operated as production wells. Wells 44, 50, and 52 are shut in during this first step. The pathways of travel of the displacing fluid are, as previously described, affected by the various wells and many of the pathways are curvilinear. At breakthrough of the displacing fluid into production wells 45, 51, and 53, the sweep pattern is as illustrated in FIGURE 8. The sweep pattern is the dark area 54 within the circumscribed area 43. For a mobility ratio of 1:1, the area 54 will constitute 53 percent of the circumscribed area 43.

In the second step of the process, referring to FIGURE 6, central well 42 is shut in. Wells 44, 50, and 52 are operated as injection wells and wells 45, 51, and 53 are continued to be operated as production wells. Displacing fluid is injected into each of the injection wells 44, 50, and 52 and petroleum is produced from production wells 45, 51, and 53. Many of the pathways of travel of the displacing fluid are curvilinear, as previously explained, and at breakthrough of the displacing fluid into the production wells, the sweep pattern is as illustrated in FIGURE 9. The sweep pattern is the dark area 55 within the circumscribed area 43 and the only portion of the circumscribed area not included within the sweep pattern is the area 56. The sweep pattern will constitute, for a mobility ratio of 1:1, 86 percent of the circumscribed area 43.

It will be noted that portions of the circumscribed area

43 included within the sweep pattern 54 are not included within the sweep pattern 55. This is due to displacement of petroleum oil during the second step of the process into a previously swept area. Thus, petroleum oil, following the completion of the first step of the process, remains in the vicinity of the shut-in wells 44, 50, and 52. With operation of these wells as injection wells in the second step of the process, however, a portion of this petroleum oil is displaced into previously swept area 54.

The well pattern illustrated in FIGURE 5 may be operated in another manner. This manner of operation is illustrated in FIGURE 7. In the first step, central well 42 is operated as an injection well and wells 44, 45, 50, 51, 52, and 53 are operated as production wells. The displacing fluid is injected into central well 42 and it advances through the formation to each of the output wells. Production of petroleum oil is from each of the production wells and some of the pathways of flow between the injection and production wells are curvilinear. At breakthrough of the displacing fluid into the production wells, the sweep pattern is as illustrated in FIGURE 10. The sweep pattern is the dark area 57 within the circumscribed area 43. The dark area constitutes 74 percent of the circumscribed area 43, for a mobility ratio of 1:1.

The well pattern illustrated in FIGURE 1 may be operated in the same manner as just described for the well pattern illustrated in FIGURE 5. Thus, displacing fluid may be injected into central well 22 and wells 23, 34, 24, 31, 25, 32, 30, and 33 may be operated as production wells in the first step. In the second step, central well 22 is shut in and either wells 23, 24, 25, and 30 operated as injection wells and wells 31, 32, 33, and 34 operated as production wells or wells 31, 32, 33, and 34 operated as injection wells and wells 23, 24, 25, and 30 operated as production wells.

In the second step, operations are as illustrated in FIGURE 6. Central well 42 is shut in. Wells 44, 50, and 52 are operated as injection wells and wells 45, 51, and 53 are operated as production wells. Displacing fluid is injected into wells 44, 50, and 52 and it advances through the formation in pathways, some of which are curvilinear, to wells 45, 51, and 53. At breakthrough of the displacing fluid into the production wells, the sweep pattern is as illustrated in FIGURE 11. The sweep pattern is the dark area 60 within the circumscribed area 43. The sweep pattern constitutes practically 100 percent of the circumscribed area.

The procedure of the invention is applicable to any type of production operation for petroleum oil where a displacing fluid is injected into the oil-containing formation. Among these procedures are gas drive, water drive, miscible flooding, and in-situ combustion. In gas drive operations, a gas such as a flue gas, carbon dioxide, natural gas, or other gas is injected into the formation into an injection well. This gas displaces the petroleum oil as it advances through the formation and forces the oil through the formation into the direction of the production wells. In water drive operations, water is injected into the formation into an injection well and the injected water displaces petroleum oil from the formation and drives it through the formation to the production wells. In miscible flooding, a material is injected into the formation through an injection well to form a fluid phase in the formation and thereafter a driving gas is injected into the formation. The material injected into the formation is one which is miscible with the petroleum oil in the formation and the driving gas is one which is miscible with the material forming the fluid phase. The driving gas forces the fluid phase through the formation into the direction of the production wells and the advancing fluid phase displaces the petroleum oil from the formation and drives it into the direction of the output wells. In situ combustion, a combustion-supporting gas is injected into the formation through an injection well and combustion of petroleum oil within the formation is initiated.

With continued injection of the combustion-supporting gas, a flame front advances through the formation consuming a portion of the petroleum oil in the formation and displacing the remainder from the formation and forcing it into the direction of the production wells. Various combinations of these procedures may be employed. For example, gas and water may be employed as the displacing fluid. Water may be used in connection with a miscible flooding procedure. Water may also be employed in conjunction with an in-situ combustion operation.

In the practice of the invention, it is not necessary that all the wells required to carry out both steps be provided at the time the first step is carried out. Those wells not employed in the first step need not be provided until the second step is carried out. Thus, wells 31, 32, 33, and 34 of FIGURE 1 and wells 44, 50, and 52 of FIGURE 5 need not be provided while the first step is carried out. During the time that the first step is being carried out, or after the final step has been carried out, these wells may be drilled and the second step thereafter carried out.

Having thus described my invention, it will be understood that such description has been given by way of illustration and example and not by way of limitation, reference for the latter purpose being had to the appended claims.

I claim:

1. A process for the recovery of liquid material from a subterranean formation penetrated by a central well surrounded by n peripheral wells arranged in a geometric pattern with said central well at the midpoint of said geometric pattern, each of said peripheral wells being equidistantly spaced from each of the adjoining peripheral wells wherein n is a whole even number of at least 6, comprising the steps of:

- (1) closing off every other of said peripheral wells,
- (2) injecting into said central well a fluid capable of displacing said liquid material contained within said subterranean formation,
- (3) producing said liquid material contained within said subterranean formation from the remainder of said peripheral wells until said displacing fluid arrives at said peripheral wells,
- (4) closing off said central well,
- (5) opening said wells closed off in step (1),
- (6) injecting into each of said peripheral wells opened in step (5) said fluid capable of displacing said liquid material contained within said subterranean formation, and
- (7) producing said liquid material contained within said subterranean formation from the remainder of said peripheral wells.

2. A process for the recovery of liquid material from a subterranean formation comprising the steps of:

- (1) drilling a well from the surface of the earth to said formation,
- (2) drilling n peripheral wells from the surface of the earth to said formation arranged in a geometric pattern surrounding said first named well, with said first named well being located at the midpoint of said geometric pattern, each of said peripheral wells being equidistantly spaced from each adjoining peripheral well and wherein n is a whole even number of at least 6,
- (3) closing off every other of said peripheral wells,
- (4) injecting into said first named well a fluid capable of displacing said liquid material contained within said subterranean formation,
- (5) producing said liquid material contained within said subterranean formation from the remainder of said peripheral wells until said displacing fluid arrives at said peripheral wells,
- (6) closing off of said first named well,
- (7) opening said wells closed off in step (3),
- (8) injecting into said wells opened in step (7) said

fluid capable of displacing said liquid material contained within said subterranean formation, and

(9) producing said liquid material contained within said subterranean formation from the remainder of said peripheral wells.

3. A process for the recovery of liquid material from a subterranean formation penetrated by a central well surrounded by six peripheral wells arranged in a hexagon with said central well at the midpoint of said hexagon comprising the steps of

- (1) closing off every other of said peripheral wells,
- (2) injecting into said central well a fluid capable of displacing said liquid material contained within said subterranean formation,

(3) producing said liquid material contained within said subterranean formation from the remainder of said peripheral wells until said displacing fluid arrives at said peripheral wells,

(4) closing off said central well,

(5) opening said closed peripheral wells,

(6) injecting into each said peripheral well opened in step (5) said fluid capable of displacing said liquid material contained within said subterranean formation, and

(7) producing said liquid material contained within said subterranean formation from said peripheral wells from which liquid material contained within said subterranean formation was produced in step (3).

4. A process for the recovery of liquid material from a subterranean formation comprising the steps of

- (1) drilling a well from the surface of the earth to said formation,
- (2) drilling six peripheral wells arranged in a hexagon surrounding said first-named well with said first-named well being located at the midpoint of said hexagon,

(3) closing off every other of said peripheral wells,

(4) injecting into said first-named well a fluid capable of displacing said liquid material contained within said subterranean formation,

(5) producing said liquid material contained within said subterranean formation from the remainder of said peripheral wells until said displacing fluid arrives at said peripheral wells,

(6) closing off said first-named well,

(7) opening said closed peripheral wells,

(8) injecting into each of said peripheral wells opened in step (7) said fluid capable of displacing said liquid material contained within said subterranean formation, and

(9) producing said liquid material contained within said subterranean formation from said peripheral wells from which said liquid material contained within said subterranean formation was produced in step (5).

5. A process for the recovery of liquid material from a subterranean formation comprising the steps of

- (1) drilling a well from the surface of the earth to said formation,
- (2) drilling three peripheral wells from the surface of the earth to said formation each located at alternate corners of a hexagon with said first-named well being located at the midpoint of said hexagon,

(3) injecting into said first-named well a fluid capable of displacing said liquid material contained within said subterranean formation,

(4) producing said liquid material from each of said peripheral wells until said displacing fluid arrives at said peripheral wells,

(5) closing off said central well,

(6) drilling three peripheral wells from the surface of the earth to said formation each located at the remaining alternate corners of said hexagon,

(7) injecting into each of said last-named three periph-

eral wells said fluid capable of displacing said liquid material contained within said subterranean formation, and
 (8) producing said liquid material contained within said subterranean formation from said first-named three peripheral wells.
